HAND SAW

Frederick Ehrsam, Oley, Pa.

Application April 9, 1953, Serial No. 24,419

Term of patent 14 years

(Cl. D93—4)

To all whom it may concern:

Be it known that I, Frederick Ehrsam, a citizen of the United States of America, residing at Oley, in the county of Berks and Commonwealth of Pennsylvania, have invented a new, original, and ornamental Design for a Hand Saw, of which the following is a specification, reference being had to the accompanying drawings, forming part thereof.

Figure 1 is a top plan view of a hand saw showing my new design.

Fig. 2 is a side elevational view of the same.

Fig. 3 is a fragmentary elevational view of the obverse side of the same.

Fig. 4 is a rear elevational view of the same.

The essential features of my design reside in the portions shown in full lines.

I claim:

The ornamental design for a hand saw, as shown and described.
